UNITED STATES PATENT OFFICE

153,238

DESIGN FOR A CONDIMENT RECEPTACLE

James R. Scheip, Tipp City, Ohio, assignor to
 H. H. Chaffee, J. A. Scheip, and J. R. Scheip, a partnership doing business as Safety Corner
 Company, Tipp City, Ohio

Application April 14, 1947, Serial No. 138,366

Term of patent 7 years

(Cl. D44—10)

To all whom it may concern:

Be it known that I, James R. Scheip, a citizen of the United States, residing at Tipp City, in the County of Miami and State of Ohio, have invented new, original, and ornamental Design for a Condiment Receptacle, of which the following is a specification, reference being had to the accompanying drawings, forming a part therewithin:

Fig 1 is a perspective view of a condiment receptacle showing my new design;

Fig 3 is a top plan view; and

Fig 4 is a side view thereof.

I claim:

Tornamintal design for a condiment receptacle substantially as shown.

JAMES R. SCHEIP.
